UNITED STATES PATENT OFFICE.

FRANK EDWARD FLYNN, OF STEUBENVILLE, OHIO, AND JAMES ROY HENSLEY, OF HOLLIDAYS COVE, WEST VIRGINIA.

DRIVE MECHANISM FOR FRICTION ROLLS.

Application filed September 14, 1923. Serial No. 662,789.

To all whom it may concern:

Be it known that we, FRANK EDWARD FLYNN and JAMES ROY HENSLEY, citizens of the United States of America, and residents, respectively, of Steubenville, in the county of Jefferson and State of Ohio, and Hollidays Cove, in the county of Hancock and State of West Virginia, have invented certain new and useful Improvements in

10 Drive Mechanism for Friction Rolls, of which the following is a specification.

This invention relates broadly to driving mechanism for rolls, and more specifically to an emergency drive for frictionally driven rolls.

The primary object of the invention is to provide, in association with the frictionally driven roll of a pair or set of rolls, a normally inactive drive mechanism which, upon 20 a substantial reduction in the speed of such roll below that of its companion roll, promptly and automatically becomes active for effecting positive driving of such roll.

As is well known, it frequently happens 25 that the frictionally driven roll of a set of rolls, especially in rolling mills, becomes unduly slowed down or stops when heavy pieces of metal are being passed between it and its companion positively driven roll; and such slowing down or stopping produces results which are at all times extremely injurious, if not actually ruinous, to the rolls.

As above indicated, it is the chief aim of 35 the present invention to provide driving means which, when the frictionally driven roll tends to unduly lag or stop, becomes instantly operative for positively driving such roll, thereby to obviate injury which 40 would otherwise result, as aforesaid.

In describing the invention in detail, reference is herein had to the accompanying drawings, in which—

Figure 1 is a side elevation of the invention, showing its application to the frictionally driven top roll of a rolling mill;

Figure 2 is a side elevation of one of the spindle members;

Figure 3 is an inner end elevation of the 50 same, showing the face of the coupling;

Figure 4 is an elevation of one face of the shiftable clutch member;

Figure 5 is a side elevation of the same;

Figure 6 is an opposite face view of said 55 clutch member;

Figure 7 is an inner end elevation of the opposite spindle member;

Figure 8 is a side elevation of the same, showing the bolt or stem upon which said clutch member is mounted; and—

Figure 9 is a similar elevation of the same, viewed from a point at a right angle to the view point in Fig. 8.

Referring to said drawings, 1 indicates the lower roll of a set of rolls of the type commonly employed in mills for the rolling of heavy metal, said roll being positively driven, as ordinarily, through a spindle 2 by which it is coupled to a drive shaft or to another positively driven roll in a train of rolls. Located over said roll 1 is a similar roll 3 which, as heretofore commonly employed, has been adapted to be driven by frictional engagement with said roll 1 or with material interposed for rolling between 75 said rolls.

In carrying out the present invention, a pinion 4 is carried by an appropriate part of, or at an appropriate point in, the drive for the lower roll 1, as on the neck of an adjacent alined roll of the train. Said pinion is disposed in driving relation to a pinion 5 carried in opposing relation thereto, as by an overlying countershaft 6 to which is coupled, as by a common form of coupling box 7, an alined stem 8 having a head 9. Also coupled to the wobble 3^a of the upper roll 3, as by a coupling box 10, is a stem 11 having a head 12. Said heads 9 and 12 are disposed in facing relation and are spaced 90 apart a suitable distance.

Fitted in a centrally located socket 13 provided therefor in the face of the head 9, and preferably fixed to said head 9, is the head portion 14^a of a pin or spindle 14 which has its opposite end loosely received in a centrally located socket 15 provided therefor in the head 12; and rotatably mounted on said spindle 14 between said heads 9 and 12 is a clutch member 16.

The head 12 has the face thereof shaped to provide a plurality of radially extending teeth or shoulders 17 which face rearwardly in respect to the direction of travel of the roll 3 to which it is coupled, as aforesaid, and the substantially triangular surfaces 18 located between said shoulders are inclined as shown. That face of the clutch member 16 which confronts the described face of the head 12 substantially conforms in shape to 110

that of the last mentioned face, so that said faces in one of their relative positions are adapted to assume close fitting interengaged relation in which forwardly facing shoulders 19 of said clutch member interlock with the shoulders 17 of the head 12, as shown in Fig. 1.

The opposite face of the clutch member 16 has a pair of diametrically opposite radially disposed shoulders 20 which face forwardly in respect to the direction of rotation of the roll 3 and which in one position of said member interlock with similar rearwardly facing shoulders 21 formed on the 15 confronting face of the head 9. Also formed on the last mentioned face of the clutch member and separated from the shoulder 20 thereof a suitable distance are two diametrically opposite radially disposed rearwardly facing shoulders 22 of 20 greater depth than said shoulders 20 which, in one position of said member interlock with similar forwardly facing shoulders 23 formed on said confronting face of the 25 head 9.

The pinion 5 is provided with a slightly greater number of teeth than the pinion 4 and is consequently driven at a speed slightly less than said pinion 4. As a result 30 of this difference in speed, the clutch drive hereinbefore described remains inoperative for driving the roll 3 so long as the speed of the latter is equal to that of the positively driven roll 1. While the speed of 35 said roll 3, frictionally driven, remains substantially that of the roll 1, the clutch member 16 occupies a position on the pin or spindle 14 in which its shoulders 19 are disengaged, or withdrawn, from the shoulders 40 17 of the head 12, and in which the shoulders 22 of its opposite face abut against the shoulders 23 of the head 9. This position of the clutch with respect to the head 12 is normally maintained due to the fact that 45 the inclined surfaces of the latter, when roll 3 is frictionally driven at the speed of roll 1, act upon the corresponding adjacent surfaces of the more-slowly rotated clutch to push the latter away from said head 12. 50 When, however, the roll 3 stops or its speed falls below that at which the head 9 is being driven, the shoulders 21 of the latter are carried forward into interlocking relation to the shoulders 20 of the clutch member 55 for positively driving the latter; and in so moving forward, the inclined surfaces 24 and 25 formed, respectively, on the head 9 and the clutch member ride over the inclined surfaces 26 and 27, respectively, of said member and said head, thus thrusting said member toward the head 12 and into the position in which the shoulders 19 of said member interlock with the shoulders 17 of said head 12. In this position the heads 9 60 and 12 and the clutch member cooperate to

positively drive the roll 3. When the friction between rolls 1 and 3 again suffices to drive the roll at the higher speed of the lower roll, the clutch member is again kicked back to its initial or normal position, 70 above described, the inclined surfaces 18 and 28 cooperating in an obvious manner to effect such shifting. One or both of the stems 8 and 11 of the heads 9 and 12, respectively, are readily shiftable in the coupling boxes 7 and 10 throughout a sufficient distance to allow the clutch 16 to move out of the position wherein its shoulders 19 are operatively interengaged with the shoulders 17 of the head 12. 80

It is wholly immaterial whether, following outward movement of the head 9 to the point where its stem 8 abuts against the countershaft 6, said stem is ever returned to the position shown in Fig. 1. Even in 85 the extreme outward position of stem 8, the head 9 will act to thrust the clutch member 16 into operative interlocked relation to the head 12 when the latter stops or slows down in speed below that of the head 9, and at 90 the same time it will occupy drawing relation to said clutch member through interengagement of its shoulders 21 with the clutch shoulders 20.

While we have herein shown and described the invention as applied to the rolls of a rolling mill, it will be understood that the same is readily applicable to any character of rolls in which one roll of a set is frictionally driven. 95

What is claimed is—

1. A drive mechanism for the frictionally driven roll of a set of rolls, said mechanism being normally inoperative for effecting driving of said roll, comprising in combination with such rolls a member located in alignment with the friction roll and positively rotated at a speed less than the normal friction speed of the latter and having a radially shouldered face, a member coupled to said roll and having a radially shouldered face, and a shiftable member interposed between the aforesaid faces and having on its opposite faces shoulders adapted to interlock with those of the faces which they confront, the last mentioned member being automatically shiftable into and out of operative relation to the roll carried member. 105

2. The combination with the frictionally driven roll of a set of rolls, of mechanism, normally inoperative, which becomes operative for driving said roll upon a substantial reduction in the speed of the latter below that of the driving roll, said mechanism comprising a member positively rotated at 110 a speed lower than the normal friction speed of said friction roll, a member coupled to said roll, said member having radially disposed shoulders on their confronting faces, and a member interposed between the said 115

confronting faces and having on its opposite faces shoulders adapted to interlock respectively with the confronting faces of the two first mentioned members for transmitting 5 rotation from the first mentioned member to the second mentioned member for driving the latter upon a substantial reduction in the speed of the friction roll, said faces of the intermediate member and those of the opposite 10 site end members being shaped to cooperate for effecting shifting of said intermediate member into and out of driving relation to the second mentioned end member with reduction and acceleration, respectively, of 15 the speed of the friction roll below and above that of the driven member.

3. In mechanism of the character described, the combination with the frictionally driven roll of a set of rolls, of a member 20 in fixed relation to said roll, a member positively driven at a speed substantially lower than that of said roll, each of said members having radially shouldered faces, and a clutch mounted intermediate said faces of 25 said member and having its opposite faces shouldered and adapted to interengage cooperatively with the shoulders of the therewith confronting faces of said members, said clutch being shiftable and the confronting 30 faces of said clutch and said members being relatively inclined to effect shifting of the clutch to and from operative position with reduction and acceleration, respectively, of 35 the speed of said roll below and above that of the positively driven member.

4. In mechanism of the character described, the combination with the frictionally driven roll of a set of rolls, of a member in

fixed relation to said roll, a member positively driven at a speed substantially lower 40 than that of said roll, each of said members having radially shouldered faces, a spindle carried centrally by one of said members, and a clutch rotatable and longitudinally shiftable upon said spindle, the opposite 45 faces of said clutch being shaped for cooperative interlocking engagement with the shoulders of the therewith confronting faces of said members, said confronting faces of 50 said clutch and said members being inclined for normally holding said clutch in inoperative position and for effecting shifting of the clutch to said position when the speed of 55 said roll exceeds that of said driven member.

5. A clutch mechanism of the character described comprising, in combination with a frictionally driven roll, a member positively rotated at a speed lower than the normal friction speed of said roll, a rotatable member shiftable toward and away from said 60 positively driven member and constantly maintained in rotation by the latter, and a third member permanently associated with and rotating with said roll, said shiftable member being automatically movable into 65 and out of driving relation to said third member with variations in speed of the roll below and above that of said driven member.

In testimony whereof we affix our signatures in presence of two witnesses.
